UNITED STATES PATENT OFFICE

112,054

DESIGN FOR A CASKET

Anthony J. Christian, Chicago, Ill.

Application June 27, 1938, Serial No. 78,094

Term of patent 3½ years

To all whom it may concern:

Be it known that I, Anthony J. Christian, a citizen of the United States, residing at Chicago, in the county of Cook and State of Illinois, have invented a new, original, and ornamental Design for a Casket, of which the following is a specification, reference being had to the accompanying drawing, forming part thereof.

In the drawing,
Fig. 1 is a side elevation of a casket showing my new design; and

Fig. 2 is an end elevation thereof.

I claim:

The ornamental design for a casket, as shown.

ANTHONY J. CHRISTIAN.
